GOLF TEE

John Mursch, Teaneck, N. J.

Application September 19, 1945, Serial No. 617,284

2 Claims. (Cl. 273—33)

1

This invention relates to golf tees and it is one object of the invention to provide a tee which may be formed of plastic or sheet metal and so formed that it may be placed upon the ground in position to support a golf ball and not be liable to turn over when subjected to the weight of a ball placed upon the tee.

Another object of the invention is to provide a golf tee having a base and an arm carried by the base and projecting upwardly therefrom in position to support a ball over the base, the arm being resilient so that the ball will be yieldably supported.

Another object of the invention is to provide a tee having a base and an arm for supporting a ball, the arm being disposed diagonally at such an angle that the head of a golf club will not be liable to strike the arm when driving a ball from the tee.

Another object of the invention is to provide a tee, wherein the diagonally disposed arm is formed at its upper free end with a head having a recessed upper surface so that when a ball is placed upon the head, it will be prevented from rolling off of the tee.

Another object of the invention is to provide a tee having its base so formed that it will rest firmly upon the ground instead of being thrust into the ground which is often hard and can not be easily penetrated by a tee of the type which must be forced into the ground in order to remain in position for supporting a ball.

Another object of the invention is to provide a tee which is simple in construction, of light weight, and cheap to manufacture.

The invention is illustrated in the accompanying drawings wherein:

Fig. 1 is a top plan view of a tee of the improved construction.

Fig. 2 is a side view of the improved tee.

Fig. 3 is a sectional view taken along the line 3—3 of Figure 1.

Fig. 4 is a view looking at the bottom of the tee.

Fig. 5 is a top plan view of a modified form of tee.

Fig. 6 is a sectional view taken along line 6—6 of Figure 5.

Fig. 7 is a top plan view of another modified form of tee.

Fig. 8 is a sectional view taken along the line 8—8 of Figure 7.

Fig. 9 is a side view of a tee having its base provided with teeth.

2

Fig. 10 is a top plan view of a modified form of tee.

Fig. 11 is a sectional view taken along the line 11—11 of Figure 10.

Fig. 12 is a top plan view of another modified form of tee.

Fig. 13 is a top plan view of a tee having an oval base.

Fig. 14 is a view of a tee having an oblong base.

Fig. 15 is a sectional view taken along line 15—15 of Figure 14.

Fig. 16 is a top plan view of another modified form of tee.

Fig. 17 is a sectional view taken along line 17—17 of Figure 16.

This improved tee is preferably formed of plastic but may be formed of sheet metal or other suitable material and has a base 1 which may be circular, as shown in Figures 1 through 8,

and have its inner and outer marginal portions formed with depending flanges 2 defining an annular channel 3 in the under face of the base. The flanges support the base slightly above the ground when the tee is set upon the ground in position for use and serve to prevent the tee from readily sliding along the ground out of a desired position.

An arm 4 is formed integral with the base 1 and extends upwardly from its inner marginal edge at an inward incline. This arm may be tapered towards its upper end, as shown in Figures 1 and 4, or of an even width throughout its length, as shown in Figures 5 and 7, and at its free inner end carries a head 5 which is of increased thickness and projects upwardly from the arm and has its upper face concaved to form a seat 6 in which a golf ball 7 will fit when set upon the head. It should also be noted that the arm may be of such length that the head 5 will be disposed centrally of the base, as shown in Figures 1 through 4, of increased length to dispose the head beyond the center of the base, as shown in Figures 5 and 6, or foreshortened to dispose the head short of the center of the base as shown in Figures 7 and 8. The fact that the head is thickened im-

parts sufficient weight and body to it to allow the ball to be firmly supported upon the head and since the arm 4 is resilient it may yield downwardly when a ball is set upon the head. The

incline of the arm disposes it in such angular relation to the head and the base that when a golf club is swung and the ball driven from the tee the head of the club may strike the ball

without striking the arm. A clean hit may thus be imparted to the ball and the ball driven from

the tee without dislodging the tee from the position in which it is set upon the ground. Instead of forming the base with flanges having smooth lower edges the outer one of the flanges 2 may be provided with circumferentially spaced teeth 8 which taper downwardly and are of sufficient length to penetrate the ground, shown in Figure 9, and firmly anchor the tee to the ground. Since the teeth anchor the base to the ground it will not have a tendency to slide along the ground when the ball is hit and driven from the tee. The diameter of the base relative to the head 5 and the ball is such that when a ball is set upon the head the tee will be prevented from tilting transversely and causing the ball to roll off of the tee.

The tees shown in Figures 10, 11 and 12 have a circular base 9 which is flat, as shown in Figure 11, and carries a resilient arm 10 extending upwardly from its inner marginal edge at an inward incline and terminating in a head 11 which is cup-shaped and has its concaved surface presented upwardly so that a golf ball will remain firmly in place when set upon the head. A tapered prong 12 extends from the base opposite the arm 10 in the form of tee shown in Figures 10 and 11 and has its free end portion 13 depressed so that it will penetrate the ground and brace the tee against sliding forwardly when the ball is struck. Instead of the single prong shown in Figures 10 and 11 the base may be formed with four prongs 14, as shown in Figure 12, which are spaced from each other equal distances about the base and serve very effectively to prevent the tee from slipping along the ground in all directions.

Instead of forming the tee with a circular base it may have a base 15 which is oval, as shown in Figure 13, oblong as shown in Figure 14, or other desired shape. The length of the base is approximately the same as the diameter of the base 9 and at one end the base 15 carries an arm 16 which extends inwardly at an upward incline and terminates in a cup-shaped head 17 upon which a ball is to rest. The arm may be of sufficient length to dispose the head 17 near the opposite end of the base from which the arm extends, as shown in Figure 13, or it may be shorter in order to dispose the head near the center of the base, as shown in Figures 14 and 15.

Another form of tee has been shown in Figures 16 and 17 wherein the base 18 is open at its

front end and has side strips 19 extending forwardly from ends of a rear cross strip 20. An arm 21 is formed integral with the rear cross strip 20 and extends forwardly therefrom at an upward incline midway the width of the base. At its front end the arm 21 carries a cup-shaped head 22 upon which a golf ball rests when set upon the tee. Instead of forming the base 18 oblong it may have other shapes.

Having thus described the invention, what is claimed is:

1. A golf tee comprising a flat base formed of sheet material and being of annular formation and encircling an open space, inner and outer marginal edges of said base being provided with downwardly projecting ground-engaging flanges, teeth extending downwardly from the outer flange and spaced from each other circumferentially thereof, and an arm extending upwardly from the inner edge of said base and disposed at an incline over the space encircled by the base and having a thick head at its free end constituting a ball-receiving seat disposed in a plane substantially parallel to the plane of the base.

2. A golf tee comprising a flat annular base encircling an open space and formed of thin sheet material, inner and outer marginal edges of said base being formed with depending ground-engaging members, and an arm extending upwardly from the inner marginal edge of said base at an incline over the space encircled by the base and terminating in a ball-receiving seat substantially parallel to the plane of the base.

JOHN MURSCH.
